APPARATUS FOR DRYING FABRICS

Frank H. Richterkessing, Jefferson County, near Louisville, Ky., assignor to W. M. Cissell Manufacturing Company, Incorporated, Louisville, Ky., a corporation of Kentucky

Application November 10, 1951, Serial No. 255,790

11 Claims. (Cl. 34—127)

1 This invention relates to drying apparatus employing a plurality of perforated drums into which damp articles, such as apparel are placed for drying in response to the forced circulation of hot and/or cold air through the drums while the said drums are rotating.

One object of my invention is to provide a drying apparatus having a plurality of rotating perforated drums, a single heater in the air inlet, a single exhaust means, and suitable partitions for dividing and directing the air stream flowing between the air inlet and the exhaust means, so that each drum has an independent stream of air flowing therethrough.

Another object of my invention is to provide a single lint trap for removing the lint collected in the independent streams of air circulated by the single exhaust means.

Another object of my invention is to construct and arrange the partitions so as to provide a relatively free and uninterrupted flow of air, and to eliminate flat horizontal surfaces which may accumulate lint and impair the performance of the apparatus.

Another object of my invention is to construct and arrange the partitions so as to direct each independent air stream diagonally downwardly through its respective drum.

Another object of my invention is to construct and arrange the apparatus so that the single heating device is a separable integral unit so that it may be lifted from the top of the machine to permit different types of heaters to be interchangeably substituted one for the other without requiring alterations in the basic unit including the casing, rotating drums, driving mechanisms, lint trap, exhaust means and electrical controls.

Another object of my invention is to construct and arrange the casing so that complete access to the rotating drums, etc., may be easily obtained by removing individual panels forming the front of the casing.

Another object of my invention is to provide electric controls that assure safe performance under various conditions of operation.

The advantages of these and other objects will be made manifest as the following description is read in connection with the accompanying drawings, in which:

Figure 1 is a front elevational view of a drying apparatus embodying the invention;

Figure 2 is a side elevational view of Figure 1 with parts broken away and parts shown in section;

Figure 3 is a front elevational view of the ap-

paratus illustrated in Figures 1 and 2, with the front panels removed, and certain parts broken away with parts shown in section; to show the construction and relation of the air dividing and air directing partitions with respect to the single heater, rotating drums, single lint trap and single exhaust means;

Figure 4 is a schematic drawing illustrating the manner in which the partitions divide and direct 10 the air to provide independent streams of air for each rotating drum from a single heater and a single exhaust means;

Figure 5 is a rear elevational view of Figure 1;

Figure 6 is a front elevational view of an integral steam heating unit that may be substituted 15 for the integral gas heating unit illustrated in connection with Figures 1, 2, 3, 4 and 5. A portion of the cabinet upon which the steam heating unit rests is indicated in dot-dash lines.

Figure 7 is a sectional view taken along lines 20 7—7 of Figure 9;

Figure 8 is a side elevational view of Figure 6;

Figure 9 is a plan view of Figure 6; and

Figure 10 is the electrical circuit diagram showing 25 the electrical connections of the various motors and control switches.

Before explaining in detail the present invention, it is to be understood that the invention is not limited in its application to the specific details of construction and specific arrangement of parts illustrated in the accompanying drawings, other than by the scope of the appended claims, as the invention is capable of other embodiments and of being practiced or carried out in various ways. Likewise, it is to be understood that the phrasology or terminology employed herein is for the purpose of description and not of limitation, and not intended to limit the scope of the invention claimed herein beyond the requirements 35 of the prior art.

Heretofore in the operation of multiple-drum drying tumblers having a single heating device and a single exhaust means, the hot, dry air from the heating device was first moved through one drum, and then through another drum, and then to the exhaust means. This operation produced many undesirable effects such as, unequal drying times for the two drums under otherwise identical conditions, heavy lint deposition on the articles in the second drum carried thereto by the air flowing from the first drum, and the unwanted introduction of cold air into the second drum when the door providing access to the first drum was opened.

The unequal drying times for the two drums

was the result of passing hot, dry air into the first drum, which immediately collected moisture from the damp apparel therein, thereby causing a considerable drop in the temperature of the air. The passing of this damp and cooler air into the second drum, in effect, withheld appreciable drying of the apparel in the second drum until the articles in the first drum were substantially dry. Thus, instead of simultaneous drying in the two drums, a more or less sequential drying condition was encountered.

As to the undesirable lint condition in the second drum, this was the result of the air moving through the first drum gathering lint from the tumbled apparel therein, and carrying same into the second drum.

As to the undesirable introduction of cool air into the second drum, when the door affording access to the first drum was opened, this was the result of the relative series arrangement of the apparatuses in the following order, heater, first drum, second drum and exhaust fan. Obviously, opening the door affording access to the first drum provided a cold air inlet into the first drum, and thus by-passed the heater providing only cool air for the second drum, as long as the door was open. Opening the door affording access to the second drum did not introduce cool air into the first drum, as this operation effectively by-passed both the heater and the first drum.

Thus, as the operator opens the doors from time to time to inspect the loads, conditions were established which further aggravated the unequal drying times of the first and second drums.

The present invention provides apparatus for eliminating these undesirable conditions, and is so doing has provided a fabric drying tumbler of (1) increased efficiency; (2) greater ease and flexibility of operation with less operator skill; and (3) structural superiority over what has heretofore been practiced in the art.

To understand thoroughly the principles involved in the present invention reference is directed to Figure 4.

In Figure 4 the numeral 1 designates an upright casing. The numeral 2 designates a heater which is removably mounted on top of the casing 1. In this embodiment a gas heater is illustrated, which is more specifically shown in Figures 1, 2, 3 and 5. However, it is to be understood that other forms of heaters, such as that illustrated in Figs. 6, 7, 8 and 9, may be substituted.

Numerals 5 and 6 indicate partitions partially surrounding drum 9, and numerals 7 and 8 indicate partitions partially surrounding drum 10. The lower end of partition 5 has a cut-off extension 5a connecting the upright side-wall of casing 1, while the partitions 6 and 7 are joined between the two drums to provide a continuous sweep-sheet from the single heater to the single lint trap, thereby providing separate chambers for each drum, 9 and 10.

The upper end of partition 8 also has a cut-off extension 8a connecting the upright side-wall of casing 1, and the sloping extensions 3a and 8b, respectively connecting the upright side-wall of the casing 1 and the lower end of partition 8, have rails formed on their lower ends to slidably receive the lint trap or drawer 3, and thus provide a smooth entrance into the single lint trap for the independent air streams flowing individually through the rotating drums 9 and 10 from the single heater 2.

In this respect it is to be understood that the partitions 5, 6, 7 and 8, together with extensions 5a, 8a, 8b and 3a, extend from the back wall of

the casing 1 to the plane of the front panels 1a, 1b forming the front wall of the casing.

It is to be noted that the upper ends of partitions 5 and 6 are positioned to divide and direct the air stream from the heater 2 into two paths, one through the upper drum compartment and the other to the lower drum compartment.

Also note that the lower ends of partitions 7 and 8 are positioned to direct the two separated air paths from the two drum compartments into the single lint trap, thus re-uniting the divided air-streams after they have passed through their respective drums.

It will be noted that partition sections 5 and 6 together with the front and back walls of housing 1 constitute a cylindrical casing surrounding drum 9, the parts 5 and 6 being spaced from each other to provide an inlet opening in the top portion of the cylindrical casing and an outlet opening in the bottom portion thereof. In a like manner partition sections 7 and 8 together with the front and back walls of housing 1 constitute a cylindrical casing surrounding drum 10 and having an inlet opening in the top portion thereof and an outlet opening in the bottom portion.

The arrows, shown in light lines in Figure 4, indicate the two separate paths for the air flowing from the single heater 2, to the single lint trap 3 and then to the single exhaust 4.

It is to be particularly noted that the partitions 5, 6, 7 and 8 are symmetrically arranged about their respective drums so as to provide a flow of air diagonally downwardly through each drum across the rotating axis thereof, and so that the air is equally distributed to the two drums 9 and 10.

In this respect it is to be noted that the drums rotate counter-clockwise, as indicated by the bold arrows 9b and 10b in Figure 3, so that the longitudinal ribs of each drum lift and roll the fabric articles substantially over the exhaust opening formed by the pairs of partitions at the lower right-hand side of each drum compartment. This arrangement forces the air to move through the tumbled garments in order to reach the exhaust opening, thus contributing materially to the drying efficiency of the apparatus.

Having thus described the basic arrangement of the elements of my invention, reference is now made to Figures 1, 2, 3 and 5 for a detailed description of one embodiment thereof. It is to be noted that the numerals of Figure 4 are employed in Figures 1, 2, 3 and 5 to indicate identical parts.

In Figures 1, 2, 3 and 5, the numeral 2 designates the gas-fired heating device, and 2a designates a perforated door or panel which is hinged at the top to provide access to the gas burner from the front of the machine.

Numerals 1 designates the upright casing having removable front panels 1a, 1b and 1c.

A door 11, affording access to the upper rotating drum 9, is pivotally mounted upon the panel 1a by hinge 14. A snap-latch 13 retains the door 11 in closed position, and a heat-resisting, glass-panel 12 permits visual inspection of the garments within the upper drum 9.

A bracket 16 is conveniently mounted upon the panel 1a for receiving the open top-end of laundry nets or bags to facilitate transfer of garments to and from the drum 9.

A lever 15 is pivotally mounted upon the hinge 14, and is arranged to open a normally-closed, electrical door-switch 21, when the door 11 is open.

A door 11a, affording access to the lower, rotating drum, 10, is pivotally mounted upon the panel 1b by hinge 14a, a snap latch 13a retains the door 11a in closed position, and a heat-resisting glass-panel 12a permits visual inspection of the garments within the lower drum 10.

A bracket 16a is conveniently mounted upon the panel 1b for receiving the open top-end of laundry nets or bags, to facilitate transfer of garments to and from the drum 10.

A lever 15a is pivotally mounted upon the hinge 14a and is arranged to open a normally-closed, electrical door-switch 22, when the door 11a is open.

The lower removable panel 1c encloses the chamber containing the lint trap 3 and suction fan 4.

The lint trap 3 is constructed of perforated metal in the shape of a drawer, and it will be noted that the lint trap or drawer 3 has a solid front panel 3b carrying a handle 3c, and that the drawer is slidably mounted upon rails formed on the lower ends of the cut-off extensions 3a and 3b.

A bumper 3d is mounted upon the removable panel 1c, to guide the laundry baskets as they are pushed to and from the machine.

In Figure 2, parts are cut-away and parts are shown in section, so as to show the longitudinal ribs 10a in the perforated drum 10, and the perforated lint trap or drawer 3.

In Figure 3, the three longitudinal ribs 9a of the upper drum 9, and the three ribs 10a of the lower drum 10, are illustrated as being located symmetrically about the rotating axis of the drum.

Referring now to Figures 2 and 5 the numeral 17 designates the motor that rotates the upper drum 9 via V-belt 17a, gear reducer 17b and drum shaft 17c.

The numeral 18 designates the motor that revolves the lower drum 10 via V-belt 18a, gear reducer 18b and drum shaft 18c.

Numeral 19 designates the motor that operates the suction fan 4, and it is to be noted that the suction fan 4 is provided with a discharge opening 4b, which is connected by duct piping to the exterior of the building, so as to discharge the humid air into atmosphere.

Motors 17 and 18 are mounted upon the upright casing 1 by suitable motor plates, while motor 19 is mounted upon the fan housing plate 4a, which is, in turn, mounted upon the casing 1.

Referring now to Figure 2, it will be noted that the gas solenoid valve 23 has a safety, pilot-valve 23a, which is actuated by a lever 26 pivotally mounted upon a stationary bearing-support 27. In lighting the gas pilot, the operator merely raises the door 2a, manually raises lever 26 and holds a match to the pilot. After a short interval of time, the pilot flame will affect a heat responsive element associated with the safety, pilot-valve 23a and retain the same actuated. At this time the operator can release the lever 26 as the heat from the pilot flame will hold the control 23a actuated until the pilot light is extinguished.

The manual gas-valve 28 controls the amount of gas flowing to the gas burner, and is used by the operator to shut-off the gas, when it is desirable to operate the apparatus as a "cold tumbler." The solenoid valve 23 automatically controls the gas flow in response to the operation of the electrical parts shown in Figure 10.

For convenience, the door 2a is provided with

a latch to retain same in raised position while the operator is lighting the pilot.

In Figure 10, the numeral 24 designates a manually-operated, toggle-switch for starting and stopping motor 17, which rotates the upper drum 9.

Numeral 25 designates a manually-operated, toggle-switch for starting and stopping motor 18, which rotates the lower drum 10.

Numeral 21 designates a normally-closed, door-switch, which is opened by lever 15, when the upper door 11 is open.

Numeral 22 designates a normally-closed, door-switch, which is opened by lever 15a, when the lower door 11a is open.

The numeral 20a designates a normally-closed switch associated with the thermostat 20 shown in Figures 3 and 4, and these contacts are opened in response to a rise in temperature, actuating the thermostat 20 via heat responsive element 20b, located in the air inlet to casing 1.

Thus, with the pilot flame burning and both doors 11 and 11a closed, contacts 20a, 21 and 22 are closed.

25. When the operator actuates switch 24, a circuit is completed from BX through the upper contact 24a, wire 29, motor 17, wire 30, door-switch 21, wire 31, door switch 22, wire 32 to CX. This completes the circuit for motor 17 causing the upper drum 9 to rotate.

A second circuit is completed from BX through the lower contact 24b, wire 33, wire 34, motor 19, to CX. This completes the circuit for motor 19 causing the suction fan to operate.

35. A third circuit is completed from BX through the lower contact 24b, wire 35, solenoid valve 23, wire 36, thermostat contacts 20a, wire 37, door switch 21, wire 31, door switch 22, wire 32 to CX. This completes the circuit for the solenoid

40. valve 23, causing the main burner of the gas heater to operate. Should the gas heat become too high, the thermostat contacts 20a open and de-energize the solenoid valve 23, thereby stopping the operation of the main burner of the gas heater until the temperature drops to a predetermined safe value.

When either door 11 or 11a is opened, the respective door switch 21 or 22 is opened, and the circuits to CX for the solenoid valve 23, and the motors 17 and 18 are opened, thus stopping the drums and cutting off the supply of gas to the main burner until the door is again closed.

Operation of the switch 25 by the operator will start motor 18, energize valve 23, and start the motor 19 similarly to that described for switch 24. In this respect it is to be understood that switches 24 and 25 are illustrated in their normally-open or "off" positions.

60. When gas heat is not employed, the thermostat 20 and solenoid valve 23 are eliminated. Thus, wires 35, 36 and 37 are omitted, but the remaining parts of the circuit are employed when a steam coil heater, such as that illustrated in Figures 6, 7, 8 and 9 is substituted. To effect the substitution the electric wires 35 and 37 are disconnected, the integral gas unit lifted from the top of the machine, and the integral steam heating unit placed upon the top of the machine and connected to a suitable source of steam via steam connections 47 and 48.

In Figures 6, 7, 8 and 9, the numeral 42 designates a main housing having an open underside communicating with the open top of the casing 1, and an opening 42a communicating with a cham-

ber formed between the two steam coils 39 and 40, and the cover 41.

The main housing 42 has a second opening 42b communicating with atmosphere.

A lever 44 is pivotally mounted upon a stationary bearing 45 carried by the housing 42, and this lever is pivotally attached at 46 to a sliding damper 43, slidably carried by horizontal rails 42c mounted on the end plates of housing 42.

When the lever 44 is moved to the left, as illustrated in Figure 9, the sliding damper 43 is moved to the right, closing the opening 42b and opening the opening 42a. Thus, in this condition, air is drawn into the machine by the suction fan 4 over the steam coils 39 and 40.

When the lever 44 is moved to the right, as indicated by the dot-dash lines in Figure 9, the sliding damper 43 is moved to the left, closing opening 42a and opening opening 42b. Thus, in this condition, cool air is drawn into the machine by suction fan 4 through the opening 42b.

It will be obvious that any degree of heat, between that of atmosphere and the maximum provided by the steam coils, can be effected by moving the sliding damper 43 to any intermediate position, where cool air through the partial opening of opening 42b is mixed with hot air coming through the partially closed opening 42a.

In Figures 6, 8 and 9 the numeral 49 designates a perforated front panel enclosing the front portion of the steam coils.

Having thus described my invention, I claim:

1. In a drying apparatus, the combination of a casing having upper and lower perforated drying drums rotatably mounted therein; an air heater communicating with the casing above the top drying drum; an exhaust fan communicating with the casing below the lower drying drum; and a partition between the upper and lower drums having an upper portion extending upwardly at one side of the upper drum and a lower portion extending downwardly at the opposite side of the lower drum to divide the casing vertically into separate compartments for the upper and lower drums and to direct hot air from the heater to the exhaust fan independently for each drum.

2. In a drying apparatus, the combination of a vertically elongated casing having upper and lower perforated drying drums rotatably mounted in the upper and lower sections thereof; an air heater communicating with the casing above the top drying drum; an exhaust fan communicating with the casing below the lower drying drum; and a partition within the casing extending from the top to the bottom thereof and dividing the casing into separate ducts for each drum, and directing hot air from the heater to the exhaust fan independently for each drum.

3. In a drying apparatus, the combination of a casing having upper and lower perforated drying drums rotatably mounted therein; an air heater communicating with the casing above the top drying drum; an exhaust fan communicating with the casing below the lower drying drum; and a curvilinear partition within the casing dividing the casing into two independent ducts extending from the top section of the casing to the bottom section thereof, one duct including the upper drum and the other duct including the lower drum.

4. In a drying apparatus, the combination of a casing having upper and lower perforated drying drums rotatably mounted therein; an air heater communicating with the casing above the

top drying drum; an exhaust fan communicating with the casing below the lower drying drum; and a partition within the casing extending from the top section of said casing downwardly along one side of the upper drum, then horizontally between the said drums, and then downwardly along the opposite side of the lower drum to the bottom section of the casing to provide independent air passageways between the heater and exhaust fan for each of the said drums.

5. In a drying apparatus, the combination of a casing; an air heater communicating with the casing at one end thereof; an exhaust fan communicating with the casing at the opposite end thereof; a curvilinear partition within the casing extending substantially between the aforesaid ends of the casing and dividing the casing into two independent compartments; and a perforated drying drum rotatably mounted in each compartment, said partition having a section curved concentrically about one side of one drum and another section curved concentrically about the opposite side of the other drum.

6. In a drying apparatus, the combination of a vertical casing; an air heater communicating with the top portion thereof; an exhaust fan communicating with the bottom portion thereof; a vertical partition extending from the top portion of the casing to the bottom portion thereof, dividing the casing into two independent air ducts; and a perforated drying drum rotatably mounted in each duct, said partition having a section curved concentrically about one side of one drum and another section curved concentrically about the opposite side of the other drum.

7. In a laundry drying apparatus, a casing comprising back and side walls, a wall member within the casing which together with the casing side walls forms separated conduits, each having an air inlet opening at the top and an air outlet opening at the bottom, upper and lower perforated drums rotatably mounted in said conduits, said wall member passing partially around one side of the upper drum and partially around the opposite side of the lower drum to form an air inlet conduit section for the lower drum and an air outlet conduit section for the upper drum, baffle means extending inwardly from said casing side walls and opposed to said wall member, heating means communicating with both of said air inlets, a common exhaust chamber at the bottom of said casing communicating with both of said air outlets and an exhaust fan communicating with said exhaust chamber.

8. The laundry drying apparatus as defined in claim 7 wherein the vertically extending wall member is generally S-shaped.

9. In a laundry drying apparatus, a casing comprising back and side walls, a wall member within the casing which together with the casing side walls forms separated conduits, each having an air inlet opening at the top and an air outlet opening at the bottom, upper and lower perforated drums rotatably mounted in said conduits, said wall member passing partially around one side of the upper drum and partially around the opposite side of the lower drum to form an air inlet conduit section for the lower drum and an air outlet conduit section for the upper drum, baffle means extending inwardly from each side wall of said casing and extending partially around said upper and lower drums, respectively, on opposite sides thereof from said wall member, heating means communicating with both of said air inlets, a common exhaust chamber at the bottom of said

casing communicating with both of said air outlets, and an exhaust fan communicating with said exhaust chamber.

10. In a laundry drying apparatus, a housing comprising front, back and side walls, a pair of perforated drums rotatably mounted in the upper and lower sections of said housing respectively, a cylindrical casing surrounding each drum and extending between the front and back walls of said housing, each cylindrical casing being provided with an inlet opening in the top wall portion and an outlet opening in the bottom wall portion thereof, said cylindrical casings being spaced from the side walls of said housing, said housing having an air inlet opening in the top section thereof above the upper drum and an exhaust opening in the lower section thereof below the lower drum, baffle means extending from one side wall of said housing to prevent air from passing around one side of the upper cylindrical casing, baffle means extending from the opposite side wall of said housing to prevent air from passing around the opposite side of the lower cylindrical casing, and baffle means connected between said two cylindrical casings to prevent air from flowing from the outlet of said upper cylindrical casing into the inlet of the lower cylindrical casing.

11. In a laundry drying apparatus, a casing comprising front, back and side walls and having an air inlet at the top thereof, a partition wall within the casing connecting the front and back walls and dividing the air entering said inlet into two separate streams, a perforated drum rotatably mounted in an upper section of said casing and

within one of said air streams, a second perforated drum rotatably mounted in a section of said casing below said first drum and within the other air stream, said partition wall passing downwardly around one side of the upper drum and spaced from the adjacent side wall of the casing to form an air inlet conduit section for the lower drum and then passing laterally between both drums and being spaced from the opposite side wall of said casing to provide an air outlet for the upper drum, baffle means within the casing connecting the front and back walls and extending inwardly from said opposite side wall and spaced from said partition wall to form an air inlet for the upper drum, second baffle means within the casing connecting the front and back walls and extending inwardly from said adjacent side wall and spaced from said partition wall to form an air outlet for the lower drum, heating means for heating the air in both air streams, a common exhaust chamber within said casing communicating with both of said air outlets, and an exhaust fan communicating with said exhaust chamber.
